CLAIM

The ornamental design for an elastic tie down strap, as shown and described.

DESCRIPTION

FIG. 1 is a perspective view as seen from the top, front, and left side of the elastic tie down strap showing our new design;

FIG. 2 is a left side elevational view thereof, the right side elevational view being a mirror image of the left side elevational view thereof;

FIG. 3 is a front elevational view thereof;

FIG. 4 is a rear elevational view thereof; and,

FIG. 5 is a top plan view thereof, the bottom plan view being a mirror image of the top plan view.
